Primary Examiner—Philip Hyder*Assistant Examiner*—Cynthia Underwood(74) *Attorney, Agent, or Firm*—Salter & Michaelson(57) **CLAIM**

The ornamental design for a mud guard, as shown and described.

DESCRIPTION

FIG. 1 is a perspective view of a mud guard showing my new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof;

FIG. 7 is a rear elevational view thereof; and,

FIG. 8 is a front view thereof illustrative of the use of the mud guard.

The portions shown in broken lines are included to show environment and form no part of the claimed design.
